subcool the liquid on its path to the evaporator 10 a heat exchange jacket 25 is arranged about the liquid coil 18 and is supplied with a portion of the liquid refrigerant cooled in the coil 17 and withdrawn from the liquid line through a connection 26 under control of a valve 27. After flowing through the jacket 25 and subcooling the liquid in the coil 18 the refrigerant is returned to an interstage connection or conduit 28 between the compressors 12 and 13. The refrigerant after cooling the subcooler is then available to cool the refrigerant flowing from the compressor cylinder 12 to the compressor cylinder 13 and thereby reduces the amount of superheat in the refrigerant in the interstage connection 28. A considerable increase in effectiveness of the refrigerating system may be obtained by reducing the superheat in the interstage connection, and in order to obtain the required low temperature, it may be desirable to employ as much as ten per cent of the refrigerant circulated through the low pressure stage.

In order to control the amount of cooling of the refrigerant in the interstage connection 28, I provide the valve 27 with a temperature responsive element or feeler bulb 30 which is responsive to the temperature of the refrigerant admitted to the compressor 13 and controls the flow of refrigerant for cooling the subcooler to maintain substantially constant the temperature of the refrigerant admitted to the compressor 13. This arrangement avoids excessively high temperatures in the high stage compressor and minimizes difficulties which might arise from overheated valves or bearings, for example. Throughout the operation of the system the control valve 27 is effective to maintain the temperature of the refrigerant at the intake of compressor 13 below a predetermined value. The provision of the main liquid to suction line heat exchanger 11, the subcooler coil 18, and the temperature control of the refrigerant in the interstage connection 28 increases the capacity and improves the efficiency of the system and facilitates the attainment of the very low temperatures required.

The modification of my invention illustrated in Fig. 2 is similar to that shown in Fig. 1 and corresponding parts have been designated by the same numerals. The evaporator 10 and cooling chamber 11 together with the valves 19 and 20 have been omitted; however, they are intended to be employed in the same manner as in Fig. 1. In the system of Fig. 2 the operation of the liquid subcooler comprising the coil 18 and the jacket 25 is controlled by a thermostatic expansion valve 31 having a feeler bulb 32 responsive to the temperature of the vaporized refrigerant withdrawn from the jacket 25. The valve 31 includes an element (not shown) responsive to the pressure in the jacket 25 and is effective to control the superheat of the vaporized refrigerant leaving the subcooler in a manner well known in the art. In order to control the temperature of the low pressure refrigerant admitted to the compressor 13, a temperature responsive valve 33 is provided to control a bypass connection 34 for admitting liquid refrigerant from the liquid line directly to the interstage connection 28. The valve 33 is controlled solely in response to the temperature of the refrigerant entering the compressor 13 through the agency of a temperature responsive element or feeler bulb 35 secured in heat exchange relation with the connection 28 at the intake of the compressor 13. The liquid refrigerant supplied to the valves 31 and 33 in Fig. 2 is

taken from the liquid line at a T-connection 36 before the liquid flows to the coil 17 in the heat exchanger casing 23 whereas in the arrangement of Fig. 1 the liquid refrigerant flows to the valve 27 after flowing through the heat exchanger. Obviously, either of these connections may be employed with the systems of Figs. 1 and 2.

The refrigerating system of Fig. 2 which provides independent control of liquid subcooling and interstage cooling is described and claimed specifically in a copending application of Wayne E. Dodson, Serial No. 521,520, filed February 8, 1944, and assigned to the same assignee as the present invention.

The refrigerating system illustrated in Fig. 3 embodies a receiving chamber for expanding and cooling the liquid. Parts of the system corresponding to those in Figs. 1 and 2 have been designated by the same numerals. Other parts of the circuit not shown in Fig. 3 are similar to the system of Fig. 1, with the exception that the pressure regulating valve 19 can be omitted, since the liquid enters the thermostatic expansion valve 26 at an intermediate pressure prevailing between the low and high pressure compressors. Liquid refrigerant expands, vaporizes, and is cooled upon entering a thermally insulated container or chamber 37. The vapor or "flash gas" is drawn off through a tube 38 and is conducted to the interstage connection 28. Cold liquid refrigerant accumulates in the lower portion of the container 37, until it is withdrawn through the thermostatic expansion valve 26, and therefrom fed into the evaporator 10. The flow of refrigerant to the chamber 37 is controlled by a temperature responsive valve 40 having a feeler bulb 41 responsive to the temperature of the refrigerant admitted to the compressor 13. It will readily be apparent that the operation of the valve 40 will determine the height of the liquid refrigerant in the chamber 37. The cooling of the liquid refrigerant in the chamber 37 is, of course, effected by the vaporization of a portion of the refrigerant under the operation of the compressor 13 in withdrawing vapor through the tube 38.

The refrigerating system illustrated in Fig. 4 employs a refrigerant circuit similar to that of Fig. 1 except that the main liquid line to suction line heat exchanger and the liquid subcooler have been arranged in a common receptacle 42 filled with suitable heat insulation. The main heat exchanger comprises a casing 23a having a heat exchange coil 11a arranged therein. In order to provide liquid subcooling a portion of the liquid line 18a between the coil 11a and the evaporator is surrounded by a tube or jacket 25a and the concentric tubes are wound about the casing 23a but not necessarily in contact therewith. Liquid refrigerant from the receiver 15 is circulated through the casing 23a under control of the temperature responsive valve 27a having its thermal element 38a arranged to be responsive to the temperature of refrigerant admitted to the compressor 13. Refrigerant vaporized in the casing 23a is returned to the interstage connection 28 for removing superheat from the refrigerant discharged from the compressor 12. The operation of the system of Fig. 4 is essentially the same as that of Fig. 1; however, the arrangement of the heat exchanger and subcooler in the insulating casing 42 makes it possible to provide a heat exchange unit as a separate element of the system and to employ the same insulation for protect-

ing both the heat exchangers from the higher temperature of the ambient air.

During the operation of the refrigerating systems illustrated in the several figures of the drawings, the temperature of the refrigerant flowing from the low pressure stage into the intake of the high pressure stage is controlled to increase the capacity and efficiency of the system and, furthermore, the efficiency is further increased by effective subcooling of the liquid refrigerant. These arrangements are simple and effective and greatly facilitate the efficient operation of the system at low temperatures.

While I have described my invention in connection with a two-stage compressor system for cooling an enclosed chamber other applications will readily be apparent to those skilled in the art. I do not, therefore, desire my invention to be limited to the particular constructions illustrated and described, and I intend by the appended claims to cover all modifications within the spirit and scope of my invention.

What I claim as new and desire to secure by Letters Patent of the United States is:

1. A multi-stage refrigerating system comprising high and low pressure compressors, an evaporator and a condenser, an interstage connection for conveying refrigerant from the outlet of said low pressure compressor to the inlet of said high pressure compressor, means for conducting liquefied refrigerant from said condenser to said evaporator, means for removing a portion of the refrigerant from said last mentioned means and for returning it to said interstage connection, and means dependent solely upon the temperature of the refrigerant at the inlet of said high pressure compressor for controlling the quantity of refrigerant admitted to said interstage connection.

2. A multi-stage refrigerating system comprising high and low pressure compressors, an evaporator and a condenser, an interstage connection for conveying refrigerant from the outlet of said low pressure compressor to the inlet of said high pressure compressor, means including a liquid refrigerant cooler for conducting liquid refrigerant from said condenser to said evaporator, said cooler being arranged to utilize a portion of the liquid refrigerant in said conducting means for cooling the liquid in said cooler and for thereafter conveying said portion to said interstage connection, and means dependent solely upon the temperature of the refrigerant at the inlet of said high pressure compressor for controlling the quantity of refrigerant admitted to said interstage connection.

3. A multi-stage refrigerating system comprising high and low pressure compressors, an evaporator and a condenser, an interstage connection for conveying refrigerant from the outlet of said low pressure compressor to the inlet of said high pressure compressor, a liquid line for conducting liquefied refrigerant from said condenser to said evaporator, a heat exchanger for subcooling the liquid in a portion of said line, means for bleeding refrigerant from said line to supply said heat exchanger and for conducting refrigerant vaporized in said heat exchanger to said interstage connection, and means dependent solely upon the temperature of the refrigerant at the inlet of said high pressure compressor for controlling the bleeding of refrigerant to said heat exchanger.

4. A multi-stage refrigerating system comprising high and low pressure compressors, an evaporator and a condenser, an interstage connection for conveying refrigerant from the outlet of said low pressure compressor to the inlet of said high pressure compressor, a liquid line for conducting liquefied refrigerant from said condenser to said evaporator, means including a first heat exchanger for utilizing vaporized refrigerant returned from said evaporator to said low pressure compressor for cooling refrigerant in said liquid line, a second heat exchanger arranged to cool liquid refrigerant in a portion of said line between said first heat exchanger and said evaporator for subcooling the liquid refrigerant in said portion of said line, means for bleeding refrigerant from said line to supply said second heat exchanger and for conducting to said interstage connection the refrigerant vaporized in said second heat exchanger, and means responsive to the temperature of the refrigerant at the inlet of said high pressure compressor for controlling the bleeding of refrigerant to said second heat exchanger.
5. A multi-stage refrigerating system comprising high and low pressure compressors, an evaporator and a condenser, an interstage connection for conveying refrigerant from the outlet of said low pressure compressor to the inlet of said high pressure compressor, means including a liquid cooler arranged between said condenser and said evaporator for conducting liquid refrigerant from said condenser to said evaporator, said cooler comprising a container arranged to collect liquid refrigerant and to separate gaseous refrigerant from the liquid therein, a conduit opening into said container below the top thereof for conveying refrigerant from said container to said interstage connection, and a valve between said condenser and said container and dependent solely upon the temperature of the refrigerant entering said high pressure compressor for controlling the flow of refrigerant to said container to maintain at a predetermined temperature the refrigerant admitted to said high pressure compressor.
6. A multi-stage refrigerating system comprising high and low pressure compressors, an evaporator and a condenser, an interstage connection for conveying refrigerant from the outlet of said low pressure compressor to the inlet of said high pressure compressor, a liquid line for conducting the liquefied refrigerant from said condenser to said evaporator, said liquid line including two heat exchange portions in series, a casing surrounding said first portion and connected in the path of vaporized refrigerant returned from said evaporator to the inlet of said low pressure compressor, a jacket surrounding said second portion of said line to form a concentric tube heat exchanger, said jacket with said second portion therein being wound about said casing, means for bleeding refrigerant from said line to said jacket for subcooling the liquid refrigerant in said second portion and for conducting to said interstage connection the refrigerant vaporized in said jacket, and means responsive to the temperature of the refrigerant at the inlet of said high pressure compressor for controlling the bleeding of the refrigerant to said jacket.
